UNITED STATES PATENT OFFICE.

ERNEST L. SMITH, OF SABULA, IOWA.

FREIGHT-CAR GRAIN-DOOR.

1,238,586.

Specification of Letters Patent. Patented Aug. 28, 1917.

Application filed January 8, 1917. Serial No. 141,219.

To all whom it may concern:

Be it known that I, ERNEST L. SMITH, a citizen of the United States, residing at Sabula, in the county of Jackson and State 5 of Iowa, have invented new and useful Improvements in Freight-Car Grain-Doors, of which the following is a specification.

The present invention relates to improvements in freight car constructions and relates particularly to grain doors for such 10 cars.

In carrying out my invention it is my purpose to provide a freight car with a metallic door that may be easily and quickly 15 positioned to close the door opening, and locked in such position, and which, when not thus employed may be arranged upon the side of the car in a firmly supported condition to occupy only a small amount of 20 space.

It is a further object of the invention to provide the door posts of a freight car with means for engaging with the flanged or cleated edges of a metallic door, said means 25 being operable to securely lock the door against the door posts as well as to permit of the removal of the door from the door opening when the said door is not required for closing the said opening.

It is a still further object of the invention to produce a metallic door for freight cars, the same having its edges flanged or otherwise provided with members that are adapted to engage with vertically arranged elements upon the door posts, one of said elements comprising a pivoted member which, when swung in one direction will interengage with one of the flanges on the door to swing the said door against the door posts 40 and to bring the other flange of the said door into tight engagement with the other element upon the door post, and to also provide means for locking the swinging element as well as means for engaging with the door 45 to retain the same against vertical movement.

It is a still further object of the invention to provide upon one of the door posts of a freight car a vertically arranged plate, to 50 eccentrically mount upon the other door post a tension bar, to provide the latter with locking means, to produce a sectional metallic door which has its ends inturned or otherwise provided with flanges one adapted to engage with the vertical plate upon one of the door posts and the other to receive the

tension bar, when the said bar is swung in a line with the post upon which it is pivoted, and whereby the said bar is swung against the side of the post to move the door 55 longitudinally to bring the flanges of the same into tight engagement with the plate and with the tension bar, and to lock the tension bar in such position whereby to effectively secure the door in operative position; the door sections having flexible elements attached thereto which are supported from the car, whereby to prevent the misplacement of the said sections, and the car having its sides provided with means for 60 supporting the door sections from adjacent the top of the said bar, when the door is not in use, said supporting means insuring the door sections against displacement regardless of the vibrations to which the door may 65 be subjected.

It is a still further object of the invention to provide a freight car with a removable metallic door which shall have simple means whereby to lock the same in operative position and to support the same when in inoperative position, one which may be easily and conveniently handled, which shall be of a comparatively cheap construction to manufacture, which shall be practical and 85 thoroughly efficient in operation.

With the above and other objects in view the improvement resides in the construction, combination and arrangement of parts set forth in the following specification and falling within the scope of the appended claim.

In the drawings:

Figure 1 is a vertical longitudinal sectional view through a portion of an ordinary box freight car having its door opening 95 closed in accordance with this invention.

Fig. 2 is a horizontal sectional view approximately on the line 2—2 of Fig. 1,

Fig. 3 is a similar sectional view but illustrating the position of the door and the arrangement of the tension bar before the latter is swung to lock the door, or as when the door is to be removed,

Fig. 4 is a sectional view substantially similar to Fig. 1, but illustrating the arrangement of the door sections when not in use,

Fig. 5 is a perspective view of the tension bar,

Fig. 6 is a detail horizontal sectional view 110 approximately on the line 6—6 of Fig. 4.

Referring now to the drawings in detail,

the numeral 1 designates a portion of an ordinary box car, and 2—2 the vertical posts at the door opening in the side thereof.

Secured to one of the posts 2 and projecting preferably beyond the inner side thereof is a vertically arranged plate 3. The projecting edge 4 of the said plate may be offset with respect to the post 2, or the plate, if desired, may be formed with a vertically arranged flange providing the same with a lip or edge 4.

The other post 2, adjacent to the top of the car, has secured thereto a plate or bracket 5 that is provided with a horizontally disposed offset portion or ear 6, the same having an opening to receive a short extension or trunnion 7 formed upon the upper edge and in a line with one of the corners of a tension bar 8. The lower edge of the bar 8 is likewise provided with a trunnion 9 arranged, of course, upon the edge of the bar provided with the trunnion 7, and the said trunnion 9 is journaled in a suitable bearing 10 that is provided upon the sill of the doorway. Pivotally secured, as at 11, to one of the flat sides of the tension bar 8, adjacent to the upper end of the said bar, is a lever 12, and this lever is adapted to be received in a suitable keeper member 13 provided upon the bracket member 5, and in this connection it is to be stated, that suitable means may, if desired, be employed for retaining the lever locked upon the keeper. Upon the post 2 to which the tension bar 8 is eccentrically journaled is a small bracket member 14 that is provided with an angular flange or stud 15, the latter designed to contact with one of the edges of the tension bar 8 when the latter is swung against the post 2, and to contact with one of the sides of the said tension bar when the latter is swung angularly with respect to the longitudinal plane of the car or in a line parallel to the sides of the post. The bracket 14 may provide a bearing member for the tension bar, while its offset member or stud, in addition to limiting the swinging of the bar in one direction, also serves as a reinforcing element for the said bar to prevent the bending of the bar at the center thereof when the latter is under strain.

The improved door may comprise a single element, or may, and as illustrated by the drawings, comprise two sections. The door 55 is constructed of suitable sheet metal and has its ends provided with continuous in-turned flanges 16 and 17 respectively, one of the said flanges designed to engage with the lip 4 of the plate 2, and the other flange 60 17 adapted to receive the outer edge of the tension bar 8, when the latter is first swung right angularly with respect to the longitudinal plane of the car, and to wholly receive the said tension bar when the latter 65 is swung against the side of the post 2 and

when in such position the lever 12 is brought to engage with the keeper member 13. By operating the eccentrically pivoted or journaled tension bar, as just described, it will be noted that the door 18 is moved longitudinally with respect to the car and swung outwardly from its end engaging the lip 4 of the plate 3 against the side of the car. With this construction and arrangement of parts the operation of the tension bar insures the tight engagement of the door 18 with respect to the elements engaging the same and the said door cannot be opened until the lever is swung free from the keeper and the tension bar turned upon its journal bearings.

To insure the door 18 against outward movement at the lower edge thereof, I preferably secure to the sill of the car between the posts 2—2 a cleat 19, and to prevent a movement of the door in an upward vertical direction, I arrange upon the confronting sides of the posts 2 suitable catch members 20 which engage with the said door 18.

While I have broadly indicated the door 90 by the character 18, the same, as previously stated, and as disclosed by the drawings, comprises two sections, the lower section A being of a greater width than the upper section B, and the said upper section B upon 95 its inner face and lower edge is formed with an offset portion or plate 21, and upon its outer face with depending flanges or fingers 22 disposed opposite the plate 21, and between the said fingers and the said plate the 100 upper edge of the section A is adapted to be received, when the sections are assembled.

It is one of the objects of the present invention to provide means for supporting the door sections A and B against the side of the 105 car when the door is not in use, and to accomplish this I secure to the uprights of the car frame, above the sheathing on the inner sides of the car, bracket members 23—23, the said brackets being disposed to the opposite sides of the doorway to receive the lower edges of the door sections A and B. The brackets are so disposed as to permit of the upper edges of the door sections being arranged only a slight distance below the 110 upper horizontal rail of the frame and consequently a vertical movement of the said sections, incident to the vibrations to which the car is subjected will be halted by contact with the said rail 24. I may, however, 115 if I find the same desirable, employ suitable latch or bolt members 25 that are secured to the rail 24 and engage with the outer faces of the door sections at the outer portions thereof, and thus positively insure the door sections against movement in a vertical or lateral direction. The longitudinal movement of the door sections is prevented by their flanges 16 and 17 being disposed between certain of the uprights in the frame 120 125 130

construction, but, in addition to this, I secure to one of the edges of each of the sections a flexible element, such as a chain 26, and these chains may have their outer links secured to a suitable eye 27, as illustrated upon the right hand side of the drawings, or be arranged for free movement in a longitudinal direction upon a guide rod 28, the latter having its ends offset and secured to the rail 24. It will be obvious that when the chain is brought to engage with the inner offset end of the said guide rod 28 the longitudinal movement of the door section inward of the car, or in the direction of the end of the car, will be limited, and the movement of the said door section in an outward direction or toward the door opening will be limited by contacting engagement with the side of one of the posts 2. In this connection it will be noted by reference to the drawings that the flanged end of the door section A, when the latter is supported upon the brackets 23, is arranged inwardly of the lip 4 of the plate 3, and this arrangement provides additional means for preventing an

outward accidental swinging of the said section.

From the above description, taken in connection with the accompanying drawings, the simplicity of the device, as well as the advantages thereof will, it is thought, be perfectly apparent to those skilled in the art to which such invention appertains without further detailed description.

Having thus described the invention, what I claim is:—

A car having a vertically disposed plate provided with a lip secured to one of the posts of its door opening, an eccentrically mounted swinging member upon the other post of the door opening, a door having flanged ends adapted one to receive the lip of the plate and the other to receive the swinging member when the latter is moved to one position, and locking means for the swinging member when the latter is fully received in the flange of the door and turned against the door post.

In testimony whereof I affix my signature.
ERNEST L. SMITH.
